UNITED STATES PATENT OFFICE.

LUTHER R. FAUGHT, OF PHILADELPHIA, PENNSYLVANIA.

BORING-BAR.

SPECIFICATION forming part of Letters Patent No. 311,652, dated February 3, 1885.

Application filed June 4, 1884 (No model.)

To all whom it may concern:

Be it known that I, LUTHER R. FAUGHT, of the city and county of Philadelphia, in the State of Pennsylvania, have invented certain new and useful Improvements in Boring-Bars, of which improvements the following is a specification.

The object of my invention, which relates to boring-bars having two transverse slots at right angles, one to the other, each adapted to receive a tool or cutter, as in my Letters Patent Nos. 241,481, 253,523, and 289,522, dated May 17, 1881, February 14, 1882, and December 4, 1883, respectively, is to provide improved means for securing one or a pair of cutters in position in the bar in such manner as to be firmly held therein and readily removed and replaced, as required.

To this end my improvements consist in a clamping-key having a flattened face upon its inclined side and a curved or segmental face upon its straight side, and in the combination of a clamping-key, as set forth, a tool or cutter, and a transversely-slotted boring-bar, all as hereinafter more fully set forth.

In an application for Letters Patent filed by me December 29, 1883, Serial No. 115,960, I have illustrated my improved clamping-key employed as the mechanical equivalent of a clamping-screw for securing a pair of cutters of special construction, and having disclaimed said key *per se* as of the invention claimed in said application, it will, in accordance with the reservation therein made to such effect, be herein described and claimed.

In the accompanying drawings, Figures 1 and 2 are longitudinal central sections at right angles one with the other, respectively, through a portion of a boring-bar embodying my invention; Fig. 3, a transverse section through the same at the line xx of Fig. 2, and Fig. 4 a longitudinal central section showing cutters of different form secured in a similar manner to those of Figs. 1 and 2.

The boring-bar A is of similar construction to that shown in my Letters Patent No. 253,523 aforesaid, having a series of transverse or diametric slots, a' , arranged in pairs and at right angles one to the other at desired intervals in the length of the bar. One of the slots of each pair is in line with and communicates with two of a series of four longitudinal grooves

or recesses, a^3 , formed in the bar A, and the other slot of each pair is similarly located relatively to the other two grooves. The slots a' serve for the reception, at any desired point, of the two boring tools or cutters, E F, which present four cutting-edges spaced equally about the axis of the boring-bar.

The cutters E and F, which are fully set forth in my application, Serial No. 115,960, before referred to, are not herein claimed. The cutter E is provided with shoulders or bearing-projections e^2 on its top, which fit against bearings in a transverse slot or opening, g^3 , formed in the bar A, said opening being, by preference, of segmental transverse section, corresponding with the curvature of the clamping-key G, to be presently described, in order to admit of the reversal of the cutters and the insertion of the key G in said slot, if desired. The cutter F passes freely through a transverse opening or passage, e , in the cutter E, and has central shoulders or bearing-projections, f , formed on its top, which fit against similar bearings on one side of the slot a . The cutters are secured in position by a transverse clamping key or wedge, G, passing through a key-slot, g , in the bar A, and having a flattened face, g' , on its inclined side, which bears against the face of the cutter E opposite that on which the shoulders e^2 are formed. The opposite or straight side of the key G has a semicircular or otherwise segmental face, g^2 , which bears against a recess of corresponding segmental form on the side of the key-slot g farthest from the cutter E. The segmental bearing of the key on its seat in the bar enables it to swivel thereon as may be required, to insure a flat thrust on the cutters and on the bar, so that the strain shall be exerted, as nearly as practicable, equally on each side of the axis of rotation. The key or wedge G may be made of greater depth, if desirable, as shown in dotted lines in Fig. 2, and in full lines in Fig. 4, and in the latter figure the key is shown as employed to secure a pair of recessed cutters similar to those shown in Patent No. 253,523, and in substitution of the key D and gib C of said patent.

My improvements are applicable in connection with one or a pair of cutters, and are independent of the specific form of cutter or cutters employed, the latter in and of them-

selves not forming part of my present invention.

I claim as my invention and desire to secure by Letters Patent—

- 5 1. A clamping-key for boring-cutters having a flattened face upon its inclined or beveled side and a curved or segmental face upon its straight side, substantially as and for the purpose set forth.
- 10 2. The combination, substantially as set forth, of a transversely-slotted boring-bar, a

tool or cutter fitting in a slot in said bar, and a clamping key or wedge fitting in a transverse slot in said bar at right angles to the cutter-slot, said key bearing by a flattened face 15 against the cutter, and by a curved or segmental face against the boring-bar.

LUTHER R. FAUGHT.
